UNITED STATES PATENT OFFICE.

OSCAR MOBERG, OF NEW BRITAIN CONNECTICUT, ASSIGNOR TO LANDERS, FRARY & CLARK, OF NEW BRITAIN, CONNECTICUT, A CORPORATION OF CONNECTICUT.

DESIGN FOR A DISPLAY-STAND.

46,934.

Specification for Design.

Patented Feb. 9, 1915.

Application filed October 29, 1914. Serial No. 869,323. Term of patent 14 years.

To all whom it may concern:

Be it known that I, OSCAR MOBERG, a citizen of the United States, and a resident of New Britain, in the county of Hartford and State of Connecticut, have invented a new, original, and ornamental Design for a Display-Stand, of which the following is a specification, reference being had to the accompanying drawing, forming part thereof.

The drawing shows a perspective view of a display stand embodying my invention.

I claim—

The ornamental design for a display stand, as shown.

OSCAR MOBERG.
